UNITED STATES PATENT OFFICE.

FRANK HEDLEY, OF YONKERS, AND JAMES S. DOYLE, OF MOUNT VERNON, NEW YORK.

GUARD LOOKOUT STATION FOR RAILWAY CARS.

1,413,913.

Specification of Letters Patent. Patented Apr. 25, 1922.

Application filed July 1, 1919. Serial No. 308,000.

To all whom it may concern:

Be it known that we, FRANK HEDLEY and JAMES S. DOYLE, both citizens of the United States, and residents, respectively, of Yonkers and Mount Vernon, county of Westchester, State of New York, have made a certain new and useful Invention in Guard Lookout Stations for Railway Cars, of which the following is a specification.

10 This invention relates to guard lookout stations for railway cars.

The object of the invention is to provide a lookout station for the guards employed on cars and particularly on cars of the type 15 used in subway and other trains.

A further object is to provide a lookout station between adjacent ends of cars in a train, which is simple, efficient and safe.

Other objects of the invention will appear 20 more fully hereinafter.

The invention consists substantially in the construction, combination, location and relative arrangement of parts, all as will be more fully hereinafter set forth, as shown 25 in the accompanying drawing, and finally pointed out in the appended claims.

Referring to the drawing,—

Fig. 1 is a view in side elevation of the proximate ends of two adjacent cars of a 30 train, showing the application thereto of a guard look-out station embodying the principles of the present invention.

Fig. 2 is a top plan view of the same.

In the operation of cars and trains, particularly of the type now commonly employed in subway service, it is the usual custom to station a guard or attendant at the ends of the cars, usually a single guard for the proximate ends of two adjacent cars, 40 whose duties are to supervise the boarding and alighting movements of passengers, open and close the gates or doors at the ends of the cars, and sometimes in certain classes of cars, to control the opening and closing 45 of the side doors at the center of the car length, to pass the starting signals forward towards the motorman at the front end of the car or train, and to perform such other services as may be required. Usually the 50 guard stands on the rear platform of the front car or the front platform of the rear car, or else partly on the one platform and partly on the other, to operate or control the door opening and closing devices. This 55 practice, however, is not satisfactory for many reasons. In the first place the space

on the end platforms are often crowded to their limit with passengers particularly at the rush hours of traffic or where the traffic is congested, and this renders the position of the guard very uncomfortable and frequently hampers him seriously in the performance of his duties, causing delays and thereby increasing the congestion. Again, being located inside the car or on the car 60 platform the guard is unable to observe the conditions at the center doors to ascertain whether the boarding and alighting of passengers is completed so as to render it safe to close the doors, and if the guard stands 65 between the car ends, partly on the platform of one car and partly on that of the other, he is unable to observe the conditions of traffic on the station platform in the regions of the center or end doors, and besides is in 70 danger of injury when occupying this position.

It is among the special purposes of the present invention to avoid these and other objections and to provide a station for the 75 guard between the ends of adjacent cars, which will be safe and wherein provision is made for accommodating the guard on a stand or support which is elevated above the level of the car floor and adjacent the 80 sides of the car where he is enabled to gain a clear unobstructed view of, and can observe traffic conditions on, the station platforms in the vicinity of the center entrance, as well as the end doors, and wherein the 85 guard is removed from the discomfort and inconvenience of being crowded and jammed by passengers packing the car platforms.

In the drawing, reference numerals 3, 4, 90 designate, respectively, the proximate ends of two adjacent cars. Upon the end wall of each car, and preferably at opposite sides of the car coupling connections, indicated at 5, Fig. 2, is secured a narrow platform 6 upon which the guard can stand, especially 95 when the traffic is heavy, and while the car or train is at a station platform, said platforms being preferably located at a convenient and suitable height above the level of the floors of the cars. The standing platforms 6, preferably extend to proximity with the planes of the side walls of the car and afford lookout stations for the guard at both 100 sides of the cars and at an elevation which enables him to command a clear view of the 105 station platform or landing, and where he is unhampered in his work by reason of 110

crowded conditions on the car platforms. To afford additional safety and comfort for the guard, arm rests or hand grips, indicated at 7, are provided, which are secured 5 to the end walls of the car at a sufficient height above the auxiliary standing platforms 6 to enable the guard to grab the same or to rest his arms thereon while standing on the supports 6.

10 Having now set forth the objects and nature of the invention, and a construction and arrangement embodying the principles thereof, what is claimed as new and useful is,

15 1. The combination with a car, of an auxiliary lookout platform secured to the exterior of the end wall of the car and near the lateral side thereof at a height above the level of the floor of the car.

20 2. The combination with a car, of an auxiliary lookout platform secured to the exterior of the end wall of the car near the side thereof, and a grab or arm rest secured to the outer surface of the end wall above 25 said look-out platform.

3. The combination with a car, of an auxiliary lookout platform secured to the exterior of the end wall of the car, and at a height above the level of the floor of the car near the side thereof, and a grab or 30 arm rest secured to the outer surface of the end wall of the car above said lookout platform.

4. The combination with the proximate ends of adjacent cars, of auxiliary lookout 35 platforms secured opposite each other to the exterior of the end wall of each car and near the sides thereof at a height above the floor level of the cars.

5. The combination with the proximate 40 ends of adjacent cars, of an auxiliary lookout platform secured to the exterior of the end wall of each car, said platforms being positioned opposite each other, and a grab rail positioned above each lookout platform. 45

In testimony whereof we have hereunto set our hands on this 24th day of June, A. D. 1919.

FRANK HEDLEY.
JAMES S. DOYLE.
